LOOSE LEAF BINDER

Adolph G. Lotter, Milwaukee, Wis., assignor to
Stationers Loose Leaf Company, Milwaukee,
Wis., a corporation of Wisconsin

Application January 20, 1936, Serial No. 59,918

14 Claims. (Cl. 129—4)

This invention relates to loose leaf binders and refers particularly to the record book type of binder.

In binders of this type, the body of leaves is impaled upon a plurality of binder posts joined at their ends to the covers adjacent their hinged connections to the back of the binder. The connections between at least one of the covers of the binder posts are detachable to allow the removal and insertion of leaves, and the connections between the post ends and the covers include socketed portions on the covers into which the ends of the posts fit.

In view of the required degree of flexibility in the connections between the covers and the post ends, when one of the covers was disconnected from the posts, the posts were easily shifted out of proper upright position by the body of leaves during the usual handling of the book, so that the re-establishment of the connection between the disconnected cover and its ends of the posts was difficult.

The possibility of having the disconnected ends of the posts shift out of line with the socketed portions on the cover to which they are attachable was exceptionally objectionable in binders equipped with means for automatically re-establishing the connection between the cover and post ends upon closure of the disconnected cover.

It is, therefore, an object of the present invention to provide simple and effective means for holding the binder posts in proper upright position at all times so that their disconnected ends are at all times in line with the socketed portions of the covers to facilitate the establishment of the connections therebetween.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a perspective view of a loose leaf binder of the type to which this invention appertains;

Figure 2 is a cross section view through the

back portion of the binder taken on the plane of the line 2—2 in Figure 1;

Figure 3 is a perspective view of the binder shown with one cover disconnected from the posts and viewing the same from the back of the body of leaves; and

Figure 4 is a perspective view illustrating a portion of the post holding unit.

Referring now particularly to the accompanying drawings in which like numerals indicate like parts throughout the several views, the numeral 5 designates the back of a loose leaf binder of the record book type having covers 6 hingedly connected thereto as at 7. Connected to the covers adjacent the hinges 7 are binder posts 8 upon which a body of leaves 9 is impaled.

The connections between the ends of the posts 8 and the covers include channel members 10 fixed to the covers, as shown, and provided with open recesses or sockets 11 to receive the end portions 20 of the posts. Slidable in the channels of the members 10 are bars 12 having hinge pins 13 arranged to cross the recesses or sockets 11 for engagement in the looped ends 14 of the posts upon inward endwise shifting of the bar. 25

The connections between the post ends and the binder covers are thus readily detachable merely by pulling the bars 12 outwardly a distance to carry their hinge pins 13 out of the looped ends 14, and to facilitate such shifting of 30 the bars 12, they are equipped with finger engaging portions 15.

To insure proper opening and closing of the binder, it is necessary to have a degree of freedom in the connections between the ends of the posts 35 and the covers and as a consequence, when one of the covers is disconnected from the posts, as shown in Figure 3, to allow the removal or insertion of leaves, the body of leaves is very apt to be shifted. Heretofore this would cause the 40 upper disconnected ends of the posts to be carried out of proper alignment with the sockets 11 on the upper cover so that before the upper cover could be reconnected to the posts, it would be necessary to shift the body of leaves and the 45 posts back and forth until the proper alignment had been effected.

In other words with past constructions, the posts were apt to tilt out of their proper upright positions, and to overcome this disadvantage and the difficulties arising therefrom, a post holding unit, indicated generally by the numeral 16, is provided. This unit consists of two flyleaves 17 adapted to be disposed between the covers and the outermost leaves. 50 55

Each flyleaf has a stiff rigid rear edge portion 18 formed of metal or other suitable material and provided with apertures 19 for the reception of the end portions of the binder posts. The apertures in both stiff edge portions 18 are inexact alignment 5 when the flyleaves are disposed one directly above the other so that as long as the flyleaves are held in these relative positions against endwise motion parallel to the back of the binder, the posts are retained in their proper upright positions.

To hold the flyleaves in proper relationship, each flyleaf has an arched back plate 20 hingedly connected thereto as at 21. These curved or arched back plates overlap and are held in overlapped relationship by inturned flanges 22 on the ends of one of the back plates and overlying the adjacent end portions of the other back plate. In this manner, the back plates are held against relative endwise shifting while lateral motion to permit the flyleaves to move toward and from each other is permitted, such lateral motion being limited by the engagement of lugs 23 on one of the back plates with abutments 24 on the flanges 22 of the other back plate.

From the foregoing description taken in connection with the accompanying drawings, it will be readily apparent to those skilled in the art to which this invention appertains, that this invention provides simple but effective means for holding the binder posts of a loose leaf binder of the type described against tilting from their proper upright positions and that the means for accomplishing this purpose forms in effect an inner cover substantially embracing the body of leaves, and that the addition thereto does not in anywise complicate the design or construction of the binder.

What I claim as my invention:

1. In a loose leaf binder, a pair of covers, a back 40 to which the covers are hingedly connected, binder posts adapted to have loose leaves impaled thereon connected at their ends to the covers adjacent their hinged connections with the back, the connections between the binder posts and at least 45 one of the covers being detachable, and interconnected means independently of the back and covers and engaging both ends of the posts for holding the disconnected end portions of the binder posts properly aligned with their cooperating portions of the cover from which they have 50 been disconnected, said interconnected means being expandible to allow immediate detachment of one of said interconnected means from the adjacent ends of the posts upon detachment of said 55 ends of the posts from their connections with the adjacent cover.

2. In a loose leaf binder, a back, covers hinged to the back, binder posts adapted to have a body 60 of leaves impaled thereon, means for connecting the ends of the binder posts with the covers, the connections between at least one of the covers and the adjacent post ends being detachable, said connections including sockets on said cover to receive the ends of the posts, and interconnected 65 expandible means directly engaging all of the posts for holding said posts against shifting in a direction parallel to the hinge axes of the covers with said ends thereof at all times in line with said sockets so as to facilitate reconnecting said cover 70 with said post ends.

3. In a loose leaf binder having hingedly connected covers, binder posts connected at their ends to said covers, the connections between at least one cover and the adjacent ends of the posts being 75 detachable, and freely slidably connected plate

members at all times engaging the opposite end portions of all of the posts to hold the same against shifting in a direction parallel to the hinge axes of the covers to maintain the ends of the posts in position for connection to their associated cover.

4. In a loose leaf binder, a back, covers hinged to the back, binder posts, means for connecting the ends of the binder posts with the covers adjacent their hinged connections with the back, said connections including socketed portions carried by the covers to receive the ends of the posts, the connections between at least one cover and the posts being detachable, and interconnected readily expansible means engaging both ends of the posts for holding one end of the posts against lateral movement in a direction parallel to the hinge axes of the covers with respect to the other end thereof so as to maintain the disconnected ends of the posts properly aligned with the socketed portions of the cover to which they are connectible.

5. In a loose leaf binder including a back, covers hinged to the back, binder posts adapted to have a body of loose leaves impaled thereon, means for connecting the ends of the posts with the covers, said connecting means including socketed portions carried by the covers, the connections between at least one cover and the posts being detachable, and means for retaining the disconnected post ends in proper alignment with the socketed portions adapted to receive the same when the connections between said post ends and the cover carrying said socketed portions are detached, said means comprising two apertured members to receive the end portions of the posts, and means connecting said members at the back of the body of leaves in such manner as to facilitate 30 allow for relative movement of said apertured members toward and from each other while holding the same against relative endwise movement.

6. In a loose leaf binder having loosely mounted binder posts adapted to have a body of leaves impaled thereon, means for holding said posts at all times substantially perpendicular to the 45 plane of the leaves, comprising two rigid members having aligned apertures to receive all of the posts adjacent their ends, and means connecting said rigid members so as to allow immediate and free movement thereof toward and 50 from each other to accommodate variations in thickness of the body of leaves while holding the same against relative endwise movement.

7. In a loose leaf binder, a back, covers hinged to the back, binder posts adapted to have a body 55 of leaves impaled thereon, sockets on the covers to receive the ends of the posts, means for holding said posts upright with the ends thereof at all times in line with the sockets to be readily receivable therein, said means comprising two rigid 60 members one to overlie each face of the body of leaves and both apertured to receive the end portions of the binder posts, a back member hingedly connected to each of said rigid members, and means connecting said back members in such 65 manner as to allow free movement of said rigid members toward and from each other to accommodate different thicknesses of the body of leaves while holding said rigid members against relative endwise shifting.

8. In a loose leaf binder, a back, covers hinged to the back, binder posts detachably connected to the covers and adapted to have a body of leaves impaled thereon, means for holding said posts parallel to each other and substantially perpen- 75

- icular to the plane of the covers when the binder is closed, said means comprising two rigid members one to overlie each face of the body of leaves and both apertured to receive the end portions 5 of the binder posts, and a telescoped back hingedly connected to the rigid members to hold the same against relative endwise shifting while permitting flatwise movement thereof toward and from each other.
10. 9. In a loose leaf binder of the record book type, a back, covers hinged to the back and having sockets, binder posts having their ends detachably received in the sockets and adapted to have a body of leaves impaled thereon, means for 15 holding the posts upright with their ends in line with the sockets even though disconnected therefrom and substantially perpendicular to the plane of the closed covers comprising fyleaves adjacent the covers and overlying the outermost 20 of the body of leaves each of said fyleaves having a stiff portion adjacent the back which stiff portion is apertured to receive the post ends, and a telescoping back joining said stiff portions of the 25 fyleaves so as to hold the fyleaves against relative endwise movement while freely permitting movement thereof toward and from each other to accommodate different thicknesses of the body of leaves disposed therebetween.
30. 10. A post holding unit for loose leaf binders of the record book type comprising a pair of fyleaves each having a stiff portion adjacent one edge, said stiff portions having apertures to receive the binder posts of a binder with which the 35 unit is associated, a back plate hingedly connected to each of said stiff edge portions of the fyleaves, and means for holding said back plates connected in overlapping relationship in such manner as to prevent relative endwise motion 40 thereof while allowing relative lateral motion to accommodate movement of the fyleaves toward and from each other.
11. A post holding unit for loose leaf binders of the record book type comprising a pair of 45 fyleaves each having a stiff portion adjacent one edge, said stiff portions having apertures to receive the binder posts of a binder with which the unit is associated, a back plate hingedly connected to each of said stiff edge portions of the 50 fyleaves, and means for holding said back plates connected in overlapping relationship in such manner as to prevent relative endwise motion thereof while allowing relative lateral motion to accommodate movement of the fyleaves toward and from each other, and means to limit the 55 movement apart of said back plates.
12. A post holding and leaf protecting unit for loose leaf binders of the record book type comprising a pair of fyleaves having stiff marginal portions along the back edges thereof which stiff marginal portions are apertured for the reception of binder posts, an arched back plate hingedly connected to each of said stiff marginal edge portions, and means on the ends of one of said arched back plates engaging the adjacent end portions of the other arched back plate to hold said back plates in overlapped relationship and to constrain the same to a limited relative lateral motion allowing movement of the fyleaves toward and from each other while preventing relative endwise movement of the back plates and consequently the fyleaves.
13. In a looseleaf binder having a back and covers hinged thereto, binder posts adapted to have a body of leaves impaled thereon, means for connecting the ends of the binder posts with the covers including socketed portions on the 20 covers, the connections between at least one cover and the adjacent ends of the binder posts being detachable, and means independent of the back and covers forming in effect a readily detachable inner cover and connected to the end 25 portions of the binder posts to hold the end portions of the posts properly aligned with the socketed portions into which they fit when said detachable connections are detached, said independent means being readily expansible to allow 30 immediate detachment from the adjacent ends of the posts upon detachment of said ends of the posts from their connections with the covers.
14. In a loose leaf binder having a back and covers hinged thereto, binder posts adapted to 35 have a body of leaves impaled thereon, means for connecting the ends of the binder posts with the covers including socketed portions on the covers, the connections between at least one cover and the adjacent ends of the binder posts being 40 detachable, fyleaves parallel to and adjacent the covers and lying between the outermost of the body of leaves and the covers, said fyleaves having stiff rear edge portions apertured to receive the end portions of the posts, and means connecting the fyleaves and holding the same against relative longitudinal motion parallel to the back of the binder while freely allowing relative movement of the fyleaves toward and from each other whereby said fyleaves hold the binder 45 posts upright at all times and maintain the disconnected ends of the binder posts properly aligned with the socketed portions of the cover engageable therewith when the connections therebetween are detached.

ADOLPH G. LOTTER.
